UNITED STATES PATENT OFFICE.

GRAHAM CHARLES DOBSON, OF NEW YORK, N. Y.

TOILET SEAT.

Application filed January 31, 1921. Serial No. 441,810.

To all whom it may concern:

Be it known that I, GRAHAM CHARLES DOBSON, a citizen of the United States, and a resident of the city of New York, borough 5 of the Bronx, in the county of Bronx and State of New York, have invented a new and Improved Toilet Seat, of which the following is a full, clear, and exact description.

The object of the invention is to provide a 10 new and improved toilet seat, which is exceedingly simple and durable in construction and arranged to accommodate either a sectional wood filling or a composition filling.

Another object is to provide a frame 15 hinge connection between the seat, the seat cover and the bowl.

With these and other objects in view, the invention consists of certain novel features of construction as hereinafter shown 20 and described and then specifically pointed out in the claim.

A practical embodiment of the invention is represented in the accompanying drawings forming a part of this specification, in 25 which similar characters of reference indicate corresponding parts in all the views.

Figure 1 is a perspective view of the improved toilet seat with a portion shown broken out;

Figure 2 is an enlarged section of one side 30 of the same on the line 2—2 of Figure 1;

Figure 3 is an inverted plan view of the rear portion of the seat showing the hinge connection; and

Figure 4 is an inverted plan view of the 35 front end of the toilet seat showing one of the bumpers.

The toilet seat in its general construction consists of a metallic flat frame 10 and 40 a filling 11 made either of wood or of a suitable composition. In case the filling is made of wood, it is formed in sections joined together in the usual manner of making ordinary wooden toilet seats. In either 45 case the filling is of unbroken continuity the same as the metallic frame 10. The metallic frame 10 is provided at its outer and inner edges with annular integral flanges 12 and 13 inclined upwardly and

inwardly towards each other, as plainly 50 shown in Figures 1 and 2, and the said flanges 12 and 13 fit into correspondingly shaped annular rabbets 14 and 15 arranged on the sides of the filling 11 so that the outer faces of the flanges 12 and 13 are 55 flush with the outer surface filling 11. It will be noticed that by the arrangement described the wooden filling 11 with its flat under surface rests firmly on the top of the flat metallic frame 10, and the said filling 60 is held in place by the inclined flanges 12 and 13, which latter prevent any part of the filling, especially if the latter is made of wooden sections, from spreading or coming apart. 65

In practice, the metallic frame 10 is preferably made of aluminum and the flanges 12 and 13 are approximately at right angles with the plane of the frame to permit of placing the filling 11 in position on top of 70 the frame 10. When this has been done, the flanges 12 and 13 are bent inward into the rabbets 14 and 15 to fasten the filling 11 in place without the use of nails, screws, adhesive substances or other fastening devices. 75

The metallic frame 10 is provided at its rear with rearwardly extending brackets 20 fastened in place by screws or similar fastening means 21 passing through the metallic frame 10 into the filling 11. The brackets 80 20 are adapted to be engaged by the usual pintle or pintles to form a hinge connection with the supporting posts attached to the bowl of the water closet to permit of swinging the toilet seat up or down on the posts. 85

The pintle also makes the usual hinge connection with the cover for the seat. The under side of the metallic frame 10 is further provided at the sides and the front with rubber blocks 25 fastened in place by suitable screws, nails or other fastening devices 90 26 extending through the metallic frame 10 into the filling 11. The rubber blocks are adapted to rest on the top of the bowl.

The toilet seat shown and described is 95 very simple and durable in construction and can be cheaply manufactured.

Having thus described my invention, I

claim as new and desire to secure by Letters Patent:—

As a new article of manufacture a toilet seat, comprising a flat metal ring-shaped frame having at its inner and outer edges integral annular flanges inclined upwardly and inwardly toward each other, and a ring-shaped filling having a flat lower face resting upon the frame and a curved upper face

presenting curved inner and outer edges 10 and provided in said edges with annular rabbets of a depth and length equal to the thickness and length of the flanges, whereby the flanges lie flush with the filling and the latter secured to the frame without additional means. 15

GRAHAM CHARLES DOBSON.
